UNITED STATES PATENT OFFICE.

STEPHEN S. MILLER, OF AKRON, OHIO.

DESIGN FOR A RUBBER TIRE.

SPECIFICATION forming part of Design No. 32,347, dated March 13, 1900.

Application filed February 14, 1900. Serial No. 5,224. Term of patent 7 years.

To all whom it may concern:

Be it known that I, STEPHEN S. MILLER, a citizen of the United States, residing at Akron, in the county of Summit and State of Ohio, have invented and produced a new and original Design for Rubber Tires; and I do hereby declare the following to be a full, clear, and exact description of the same, reference being had to the accompanying drawings, forming a part thereof.

In said drawings, Figure 1 is a side elevation of the tire according to my design. Fig. 2 is an edge view on the same scale as Fig. 1, one-quarter of the tire being cut out to show the inner side and a cross-section. Fig. 3 is a cross-section on a larger scale.

The tread or outer portion 1 is rounded, as usual in such tires, and the inner side is re-

cessed and rounded, as indicated at 2, to form inwardly-extending flanges 3 at the inner corners of the tire. Formed around the sides of the tire are small angular shoulders 4.

The leading feature of my design is the inner portion formed with the small angular shoulders 4, the inwardly-extending flanges 25 3, and the rounded inner side 2.

What I claim is—

The design for a rubber tire substantially as herein shown and described.

In testimony whereof I affix my signature 30 in presence of two witnesses.

STEPHEN S. MILLER.
